Horace Freeman
Esq. ATTORNEY

UNITED STATES PATENT OFFICE.

GEORGE F. MILLER, OF NEW YORK, N. Y.

JOINT FOR FILTER-PRESS DEVICES.

1,313,318.

Specification of Letters Patent. Patented Aug. 19, 1919.

Application filed March 31, 1919. Serial No. 286,399.

To all whom it may concern:

Be it known that I, GEORGE F. MILLER, a citizen of the United States, residing in the city of New York, county of New York, borough of Manhattan, and State of New York, have invented certain new and useful Improvements in Joints for Filter-Press Devices, of which the following is a full, clear, and exact specification.

10 My invention relates to filter press devices and refers particularly to a connecting means between the heads and side bars of pressure filter presses.

Filter presses of this character are usually 15 constructed of two fixed oppositely opposed heads, side bars and series of filter press plates and filter press frames carried by and movable upon the side bars. A movable follower operated by screw means from one 20 of the heads abuts the plates and frames upon each other and upon the other head, filter cloth being interposed, considerable pressure being thus employed in order to make tight jointures between the plates and 25 the frames to allow of successful and practical filtering.

All of the stress therefore, is exerted 30 against the two heads tending to force them apart and as these heads are fixedly attached to the side bars, it is evident that the jointure between the heads and the side bars must be particularly secure in order to withstand the strain to which the heads and side bars are thus subjected.

35 Numerous methods are employed to accomplish this result, but they are either heavy and cumbersome in construction or of such a character as to materially weaken the tension strength of the side bars.

40 The device of my invention overcomes these disadvantages and presents a means whereby the jointure between the heads and the side bars may be produced without undue weight of material and without lessening 45 the tension strength of the side bars.

In a broad way, my device comprises a filter press head, a lug of which extends through a proper opening in the face of the side bar and a reinforcing member, all of 50 which are firmly locked together.

In the particular form of the device of my invention disclosed in the accompanying drawings, similar parts are designated by similar numerals.

Figure 1 is a broken top plan view of a 55 filter press including a device of my invention.

Fig. 2 is a broken side plan view of my device.

Fig. 3 is a section through the line 3—3 60 of Fig. 2.

Fig. 4 is a plan view of a reinforcing member.

Fig. 5 is an end view of Fig. 1, partly in section.

Fig. 6 is a broken plan view of a side bar.

The particular form of the device of my invention, shown in the accompanying drawings, comprises two parallel channel-shaped side bars 10, 10 fixedly attached to 70 the heads 11 and 12 which are fixedly attached to, and supported by, a standard 13 at each end thereof.

The means of attaching each side bar 10 to the heads 11 and 12 is as follows:— 75

An angular opening 14 is made in the body of each side bar 10 in the end portion thereof, through which the lug 15 of the head 11 passes, the lug 15 fitting snugly within the opening 14. A reinforcing member 16 has an opening 17, similar to the opening 14, through which the lug 15 also extends. The reinforcing member 16 abuts upon the face of the channel side bar 10, and has an extended member 18 at right 85 angles to the portion 16 and abuttable upon the head 11 and the end of the side bar 10. A plate 19 abuts upon the head 11, the side bar 10 and the reinforcing member 16. A screw bolt 20, extends through the plate 90 19 and threads within an opening within the lug 15, the plate 19 being held in position by the screw bolts 19', 19'.

To assemble the device, the side bar 10 is placed within the recess 21 of the head 11, 95 the lug 15 extending through the opening 17. The reinforcing member 16 is abutted upon the face of the side bar 10, the extended portion 18 abutting upon the face of the head 11 and the ends of the side bar 10, the lug 15 extending through the opening 17. The plate 19 is then placed in position 100 and the whole firmly fixed by setting up the screw bolt 20.

Each side bar 10 is thus fixedly attached 105 to both heads 11 and 12. Fig. 1 illustrates a filter press of this construction with a series of filter press frames and filter press

plates assembled in the usual way. When the follower is moved inwardly by means of the screw 22 threaded within the head 12, the plates and frames will be pressed upon each other and against the head 11, a very considerable pressure being necessary in order to form a proper construction for filtering purposes.

It is evident therefore that there is a 10 strong outward stress upon the two heads 11 and 12 and that their attachment to the side bars 10, 10 must be of a most secure character.

This outward stress of the heads is exerted by the lugs 15, 15 upon both the side bars 10, 10, the reinforcing members 16, 16 and their extended portions 18, 18, and any loss of strength of the side bars 10, 10 by reason of the openings 14, 14 is more 20 than compensated by the reinforcing members 16, 16 which are fixedly attached to the lugs 15, 15 abutting upon the faces and ends of the side bars 10, 10 and the faces of the heads, the lugs 15, 15 extending 25 through openings in the reinforcing members 16, 16.

While I have shown the use of channel-shaped side bars, it is evident that my form of construction can be similarly applied 30 to side bars of other shapes, as angle irons, flat irons, etc.

I do not limit myself to the particular size, shape, number or arrangement of parts as shown and described, all of which may 35 be varied without going beyond the scope of my invention as shown, described and claimed.

What I claim is:—

1. In a device of the character specified, in 40 combination, a filter press head, a recess within each opposite side face of the head capable of receiving a side bar, a side bar within each recess, an opening through the face of each side bar, a reinforcing member 45 abuttable upon the face of each side bar, an opening through each reinforcing member, a head lug placeable through the opening in a side bar and the opening in the reinforcing member and means for preventing 50 the movement of the side bars.

2. In a device of the character specified, in 55 combination, a filter press head, a recess within each opposite side face of the head capable of receiving a side bar, a side bar within each recess, an opening through the face of each side bar, a reinforcing member 60 abuttable upon the face of each side bar, an opening through each reinforcing member, a head lug placeable through the opening in a side bar and the opening in the reinforcing member and means for retaining the abutment between the side bars and the reinforcing members.

3. In a device of the character specified, 65 in combination, a filter press head, a recess

within each opposite side face of the head capable of receiving a side bar, a side bar within each recess, an opening through the face of each side bar, a reinforcing member abuttable upon the face of each side bar, 70 an opening through each reinforcing member, a head lug placeable through the opening in a side bar and the opening in the reinforcing member and means for fixedly attaching the side bars to the reinforcing 75 members.

4. In a device of the character specified, in combination, a filter press head, a recess within each opposite side face of the head capable of receiving a side bar, a side bar 80 within each recess, an opening through the face of each side bar, a reinforcing member abuttable upon the face of each side bar, an opening through each reinforcing member, a member integral with each reinforcing member abutting upon the face of the head, a head lug placeable through the opening in a side bar and the opening in the reinforcing member and means for preventing 85 the movement of the side bars. 90

5. In a device of the character specified, in combination, a filter press head, a recess within each opposite side face of the head capable of receiving a side bar, a side bar within each recess, an opening through the 95 face of each side bar, a reinforcing member abuttable upon the face of each side bar, an opening through each reinforcing member, a member integral with each reinforcing member abutting upon the face of the head, 100 a head lug placeable through the opening in a side bar and the opening in the reinforcing member and means for fixedly attaching the side bars to the reinforcing members. 105

6. In a device of the character specified, 110 in combination, a filter press head, a recess within each opposite side face of the head capable of receiving a side bar, a side bar within each recess, an opening through the face of each side bar, a reinforcing member 115 abuttable upon the face of each side bar, an opening through each reinforcing member, a head lug placeable through the opening in a side bar and the opening in the reinforcing member, a plate abuttable upon the head and the reinforcing member and means for fixedly attaching the head, the reinforcing member and the plate. 120

7. In a device of the character specified, in combination, a filter press head, a recess 125 within each opposite side face of the head capable of receiving a side bar, a side bar within each recess, an opening through the face of each side bar, a reinforcing member abuttable upon the face of each side bar, an opening through each reinforcing member, a head lug placeable through the opening in a side bar and the opening in the reinforcing member, a plate abuttable upon the head, the reinforcing member and the 130

- side bar and means for fixedly attaching the head, the reinforcing member, the side bar and the plate.
8. In a device of the character specified, in combination, a filter press head, a recess within each opposite side face of the head capable of receiving a side bar, a side bar within each recess, an opening through the face of each side bar, a reinforcing member abuttable upon the face of each side bar, an opening through each reinforcing member, a member integral with each reinforcing member abutting upon the face of the head, a head lug placeable through the opening in a side bar and the opening in the reinforcing member, a plate abuttable upon the head and the reinforcing member and means for fixedly attaching the head, the reinforcing member and the plate.
9. In a device of the character specified, in

combination, a filter press head, a recess within each opposite side face of the head capable of receiving a side bar, a side bar within each recess, an opening through the face of each side bar, a reinforcing member 25 abuttable upon the face of each side bar, an opening through each reinforcing member, a member integral with each reinforcing member abutting upon the face of the head, a head lug placeable through the 30 opening in a side bar and the opening in the reinforcing member, a plate abuttable upon the head, the reinforcing member and the side bar and means for fixedly attaching the head, the reinforcing member, the side bar 35 and the plate.

Signed at New York city, in the county of New York and State of New York, this 27th day of March, 1919.

GEORGE F. MILLER.
